UNITED STATES PATENT OFFICE

2,571,942

MACHINE FOR FEEDING PAPER

Rudolph Properzi, East Rochester, N. Y.

Application September 22, 1948, Serial No. 50,621

7 Claims. (CL. 271—36)

1

In the art of printing and box making etc., it is necessary to feed sheets of paper, cardboard, etc., one after another from a pile of paper or cardboard etc.

The object of this invention is to provide a machine that will feed sheets of paper, cardboard, etc., consecutively from a pile of such sheets.

Another object of the invention is to provide a machine that will adjust itself to the pile of sheets automatically as the pile of sheets become reduced in height.

Another object of the invention is to provide a machine that will feed the sheets either at high speed or low speed or speeds in between as may be desired, the machine being adjustable to take care of such variations of speed as it may be desired.

These and other objects of the invention will be illustrated in the drawings, described in the specification and pointed out in the claims at the end thereof.

In the drawings:

Figure 1 is a front elevation of the machine for feeding sheets of paper or cardboard from the top of a pile of such sheets.

Figure 2 is an end elevation of the machine, looking at the machine as shown in Figure 1 from the left.

Figure 3 is a section taken on the line 3x, 3x of Figure 1 looking at the machine from the left.

Figure 4 is a vertical section of the ball bearing through the pillow block showing the ball bearing in the pillow block under the tilting table.

In the drawings, like reference numerals indicate like parts.

In the drawings, reference numeral 1 indicates the base which supports the machine, 2 indicates an upright sleeve positioned on the base. In this sleeve slides an upright shaft 3 which can be moved up and down in the sleeve and clamped at any desired position therein by the set screw 4. On top of the shaft 3 is an enlarged head 5, which is perforated at 6 and supports a horizontal bar 7. This bar projects to the right as shown in Figure 3 and extends over the table 8 on which the sheets of paper or cardboard are carried. This horizontal bar can be extended to the right in Figure 3 to any desired length that is needed for conveniently feeding the sheets. It is fastened in the enlarged head 5 through which it passes by the set screw 9.

On this horizontal bar is supported the tilting table 10. This table 10 is preferably made of sheet metal and is conveniently made about

2

thirty-one inches long and about eight inches wide and on each long edge of the table is bent a flange 11 and 12.

Fastened under this table 10 and adjacent to the flanges 11 and 12 are the bearing pillow blocks 13 and 14. In each of these pillow blocks is carried the outside annular or ring shaped member 15 of the ball bearing and on the bar 7 is carried the inside ring member 16 of the ball bearing with balls or rollers 17 between these two members. These pillow blocks are fastened to the table 10 by bolts and nuts indicated at 18. These ball or roller bearings permit the table 10 to tilt or rock easily on the bar 7. In order to limit the tilting or rocking of the table 10, I provide a cross bar 19 that is pivotally mounted on the shaft and is clamped to the shaft by a set screw 20. The ends of this cross bar 19 is provided with studs 21a and 21b which are threaded into the ends of the cross bar and are turned upward from below to a suitable extent for a purpose that will presently be described.

On table 10 is provided an electric motor 22, a hydraulic transmission variable speed 23 and a worm gear reducing unit 24. Each of these units has a shaft. The axes or shafts of these three units are placed in line with each other as is indicated at 25 and 26.

The electric motor 22 is stock equipment, preferably about $\frac{1}{3}$ H. P.

The variable speed hydraulic transmission is a stock equipment of a well-known type and the particular unit in this case bears Patent No. 2,313,407.

The shaft of the electric motor ordinarily turns with a speed of 1750 R. P. M. The variable speed transmission can vary this speed from 1750 R. P. M. to 0 R. P. M. or increase it from 0 R. P. M. to 1750 R. P. M. That is to say, while the shaft at the right of the variable speed transmission will always turn at 1750 R. P. M. The shaft at the left of the variable speed transmission will turn at any lower angular velocity as may be desired. The variations in speed are secured by adjustments of the transmission device that constitute no part of this invention.

The variable speed hydraulic transmission has a hand wheel 23a on the side thereof by turning which, the ratio of varying the speed can be changed at will.

The worm gear reduction device 24 is a stock equipment and reduces the speed of the shaft at the left hand end of the hydraulic transmission by a factor of $12\frac{1}{2}$ to 1 and this is a fixed ratio that is not changed and the above variations in

the speed of feeding include this factor of this worm gear device whatever that factor may be.

By these adjustments above described the apparatus can be set to deliver eighty-four sheets per minute at the high speed. At three-quarter speed it will deliver sixty-six sheets per minute and at one-half speed it will deliver forty-six sheets per minute. At one-quarter speed it will deliver twenty-six sheets per minute and at low speed it will deliver one and one-half sheets per minute. These figures are based on the feeding of sheets that are forty inches long. Sheets of one-half that length will be fed twice as fast. Sheets of one-quarter that length will be fed four times as fast, etc.

For the purpose of this specification we will assume that the electric motor 22 weighs about twenty pounds and that the hydraulic transmission weighs about eighteen pounds plus the weight of a quart of oil, which is the liquid used therein; and that the worm gear weighs about eleven pounds plus about one-half pint of oil.

The three units above described are placed on the table 10 with reference to the center of the bar 7 so that when the table is in horizontal position the left hand end of the table or the end of the table that carries the feed wheels is out of balance to the extent that it has the downward thrust of about eight ounces. In this position the feed wheels are about 3 $\frac{1}{2}$ " above the table. When the left hand end of the table 10 inclines downwardly from the horizontal position, this downward thrust will increase partly according to the sine of the angle which the table makes in its then inclined position with the position which the table had when it was in balance and it will also increase partly because of the shifting of the load over the center of the bar 7.

It has been found by test of a full size apparatus, which has been made that when or just before the feeding wheels 27 reach the stationary table 8 shown in Figure 1, the left hand end of the table will weigh or have a downward thrust of about four and one-half pounds. When the table is half way between the horizontal position and the position last described, the end of the table will have a downward thrust of about three pounds.

These weights or pressures insure good traction by the feed wheels on the paper and the cardboard being fed.

For the purpose of more nearly equalizing the balance and the unbalance of the table 10 a counterweight 10a is provided at the right hand end of the table and under it as shown in Figure 1. The weight of this counterbalance is preferably just enough to provide the balance or unbalance as above described. The weight of this counterbalance can be decreased by boring one or more holes therein, in which case the feeding wheels 27 and 28 will bear more heavily on the sheets at the starting point. Or the weight of it can be increased or the effect of the counterbalance can be increased by adjusting it to the right or it can be decreased by adjusting it to the left from the position shown on the table 10 in Figure 1.

The center of gravity of the assembly is above the tilting table 10 and is preferably to the left of a radial line drawn from the center of the bar 7 and up through and perpendicular to the table when in horizontal position.

When the center of gravity of the assembly is placed a little to the right of the center of the bar 7, the table will be in balance, but will not

necessarily be horizontal. When it is placed further to the right, the table 10 will contact with the stud 21b and will stay put idly in that position. The stud 21b must be adjusted to correspond.

The angle to which the table is permitted to tip is limited by the adjustment of the stud 21a and this stud is set so that the two wheels 27 and 28 will stop feeding when only a few sheets remain on the table 8. The other stud 21b is set so that when the table is tilted in the other direction, the left hand end of the table will rise a little above horizontal in which position it will stay put. While it is in this position more sheets can be placed on the stationary table 8 and the operation of feeding the sheets can then be resumed by tilting the table 10 down at the left.

On the worm gear 21 is a transverse shaft 24a on which is carried a pulley 30 of large diameter. This drives a belt 31 which in turn drives a small pulley 32, which pulley is carried on a shaft 33. This shaft is mounted to rotate in bearings 34, 35 supported from the underside of the table 10. The feeding wheels 27 and 28 have rubber tires which bear on the sheets to be fed.

The width of the stationary table 8 in this case is thirty-inches and as shown the feed wheels are intended to feed sheets thirty inches in width. If the sheets are narrower than thirty inches, then the feeding apparatus will be set over to the left as shown in Figures 2 and 3 so that the feed wheels 27 and 28 will bear on the sheets centrally thereof, which will secure proper feeding of the sheets.

In operation the sheets of paper or cardboard, etc. are placed in a pile on the table 8 at any desired depth. The variable speed transmission 23 is adjusted to feed the sheets of paper, etc. at the desired speed and the table is then tilted down on the left and the feed wheels will come in contact with the sheets on the top of the pile on the table 8 and will immediately begin feeding the sheets one after another until the table 10 has tilted down far enough to be arrested in its further movement by the set screw 21a.

The table 10 can then be lifted at the left hand end, more sheets can be placed on the table and the feeding can be resumed and the operation can in this way be carried on indefinitely.

The assembly that is carried by the bar 7 can be raised and lowered from the pedestal by hydraulic pressure or otherwise and the stationary table can be raised and lowered in like manner so that the space between the feed wheels and the table can be increased or decreased as may be desired.

I claim:

1. In a machine for feeding sheets of paper, the combination of a horizontal shaft, a bearing mounted to tilt on said shaft, a table fastened on said bearing and extending on both sides thereof and adapted to tilt therewith, a feed wheel mounted upon and under the table near one end thereof, driving mechanism mounted on the table, gearing between the driving mechanism and the feeding wheel adapted to drive the feeding wheel, the center of gravity of said table, feed wheel, driving mechanism and gearing being located above said shaft, whereby tilting said table may position said center of gravity to one side or the other of said shaft, and stop means for holding the table in a predetermined position, when tilted in one direction with the wheel elevated.

2. In a machine for feeding sheets of paper,

the combination of a horizontal shaft, a bearing mounted to tilt on said shaft, a table fastened on said bearing and extending both ways therefrom, a feed wheel mounted upon and under the table near one end thereof, means for driving the feed wheel mounted on the table, said table having a center of gravity above said shaft, and being in balance in a central position and out of balance when tilted in either direction from the central position, means for holding the table in a predetermined position when tilted to one side of said central position, and said wheel being adapted to bear against a stack of paper sheets by gravity when the table is tilted to the other side of said central position.

3. In a machine for feeding sheets of paper, the combination of a horizontal shaft, a bearing mounted to tilt on said shaft, a table fastened on said bearing and extending both ways therefrom, a feed wheel mounted under the table near one end thereof, means for driving the feed wheel mounted on the table, said table and means having a center of gravity located above said shaft and being in balance in a central position, adjustable screws on each side of said bearings and adapted to limit movement of said table when tilted to one side or the other of said balanced central position.

4. In a machine for feeding sheets of paper, the combination of a horizontal shaft, a bearing mounted to tilt on said shaft, a table fastened on said bearing and extending on both sides thereof and adapted to tilt therewith, a feed wheel under the table near one end thereof, driving mechanism on the table, gearing between the driving mechanism and the feeding wheel adapted to drive the feeding wheel, said table with said parts having a center of gravity above said shaft and being in balance in a central position, said table being capable of being tilted through a certain angle to one side of said central position or the other, means for limiting the tilting movement of the table at the end of either of said angular positions.

5. In a machine for feeding sheets of paper, the combination of a horizontal shaft, a bearing mounted to tilt on said shaft, a table fastened on said bearing and extending both ways therefrom, a feed wheel or wheels mounted under the table near one end thereof, means for driv-

ing the feed wheel or wheels mounted on the table, said table and elements mounted thereon having a center of gravity above said shaft and being in balance in a central position, said wheel being adapted to bear upon a stack of paper sheets when said table is tilted to one side of said central position, whereby gravity acts to hold said wheel in feeding contact with the uppermost of said sheets.

10 6. In a machine for feeding sheets of paper, the combination of a horizontal shaft, a bearing mounted to tilt on said shaft, a table fastened on said bearing and extending both ways therefrom, a feed wheel or wheels mounted under

15 the table near one end thereof, means for driving the feed wheel or wheels on the table, said table being in balance in a central position at or near the horizontal with the center of gravity of the table and elements thereon being located above said shaft, and means for limiting movement of the table by gravity to predetermined positions on either side of said central position.

20 25 7. In a machine for feeding sheets of paper, the combination of a shaft, a bearing mounted to tilt on said shaft, a table fastened on and above said bearing and extending both ways therefrom, a crossbar pivotally mounted on said shaft, means for clamping the crossbar in a fixed position on said shaft at or near the horizontal, studs adjustably mounted on said crossbar, adapted to engage said table, said studs on the crossbar being adapted to limit the tilting of the table in either direction.
